UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

FOLDING MACHINE

Application filed March 22, 1928. Serial No. 263,909.

The principal objects of the invention are to provide means for receiving the longitudinal folded edge of a web coming from the former, to prevent the mis-aligning of the loose ends of the papers on account of the greater thickness at the folded edge; to provide the rolls or cylinders about which the web travels with grooves for receiving the folded edge so as to allow it plenty of room and prevent its getting the papers out of place on account of this thickness; and to provide a collar located in advance of the folding couple with a fluted edge for the same purpose.

15 Other objects and advantages of the invention will appear hereinafter.

Reference is to be had to the accompanying drawings in which

Fig 1 is an end view in section of a part 20 of a folding mechanism to which this invention can be applied; and

Fig. 2 is a developed side view showing the application of this invention to several of the rotary members.

25 When newspapers are folded over the nose of the former, the longitudinal folded edge is generally left slightly uncreased, due to the fact that the nipping rolls between which it is led cannot be adjusted too tightly as they 30 are considerably accelerated in speed and, having a knurled surface, cannot be expected to pinch the paper too tightly. For this reason the folded edge of the paper is expanded and in going around the cylinders, has a 35 tendency to mis-align the loose ends of the pages due to the greater thickness of the paper along the folded edge.

The invention is shown as applied to a folding couple comprising a folding cylinder 40 10 and a cutting cylinder 11 to which is added a yielding cylinder 12. The web passes through the nipping rollers 13 in contact with the yielding cylinder and then into the folding couple. The folded edge of the web, 45 after it comes over the former, assumes the position indicated at 14 in Fig. 2.

In order to prevent the above mentioned difficulties I provided the rotary members or some of them, in contact with which the web 50 passes, with a circumferential groove 15 at

one end. This groove is located so that the fold 14 will enter it and the loop at the edge will run along in this groove and thereby avoid the mis-alignment which this fold often causes otherwise.

I have shown these grooves 15 in both members 10 and 11 of the folding couple and also in the yielding cylinder 12. It will be seen that on account of providing this space for receiving this folded edge, its additional thickness can cause no trouble, particularly if it is provided in all the cylinders below the nipping rolls. It also acts as a guide for this fold.

Although I have illustrated and described 65 only one form of the invention I am aware of the fact that modifications can be made therein by any person skilled in the art without departing from the scope of the invention as expressed in the claims.

70 Therefore, I do not wish to be limited in these respects but what I do claim is:—

1. A folding machine having a folding couple, the two cylinders of which are provided with circumferential grooves near one 75 end to receive the longitudinal folded edge of a folded web passing between them, for the purpose described.

2. A folding machine having a cylinder in contact with which the web travels, on which 80 is a circumferential groove near one end to receive the folded edge of a web passing over it.

3. In a folding machine, the combination 85 with a folding couple, of a roller located in position to engage the web, said roller having a groove around its circumference near the end to receive and guide the longitudinally folded edge of the web.

4. In a folding machine, the combination 90 with a folding couple, of a roller located in position to engage the web before it passes into the folding couple, the said roller having a groove around its circumference near the end where it will receive the longitudinally 95 folded edge of the web to prevent mis-alignment of the web.

In testimony whereof I have hereunto affixed my signature.

HENRY A. WISE WOOD.
